[57] CLAIM

The ornamental design for a combined flower pot and
tray therefor, as shown and described.

DESCRIPTION

FIG. 1 is a front elevational view of a combined flower
pot and tray therefor showing my new design;
FIG. 2 is a top plan view of FIG. 1;

FIG. 3 is a front elevational view with the tray omitted
for clarity of disclosure;

FIG. 4 is a bottom plan view of FIG. 3;

FIG. 5 is a top plan view, with the pot omitted for
clarity of disclosure; and,

FIG. 6 is a bottom plan view of FIG. 5.
